FABRICATED BUILDING CONSTRUCTION

Francis Malcolm Crowe, Burlingame, Calif.

Application March 16, 1931, Serial No. 522,833

8 Claims. (Cl. 72—1)

This invention relates generally to the construction of houses and other buildings, and particularly to the construction and erection of exterior and interior walls thereof.

- 5 It has been generally realized that the use of more permanent and fire-safe materials will result in a superior building, but the application of such materials to dwellings has been limited up to the present time, due chiefly to the prohibitive 10 high cost. The benefits of mass production, which have reduced costs in other lines of industry, have not reached this field to any extent, although it has long been appreciated that a reduction in cost might be achieved if certain 15 building operations, usually performed exclusively on the job, could be transferred to a factory production basis.
- 20 Factory fabrication of steel frames for houses has been attempted, in conjunction with the usage of more permanent supplementary materials, such as fire proof lathing in place of wood lath. However increased total cost has characterized all such efforts, presumably because such fabrication involves only the structural framework which is 25 a small proportion of the building as a whole and because savings resulting from quantity production of this portion of the construction are not sufficient to offset the higher cost of the better materials involved.
- 20 In evolving the present invention I have appreciated that certain factors must be taken into consideration and certain problems solved. For example it is essential that some degree of flexibility be allowed as to the size, shape and arrangement 35 of rooms, the number and positioning of doors and windows, the color and texture of wall finish, the number and location of lighting fixtures and other electrical outlets, and as to various other details. Likewise it is desirable that no objectionable features be introduced, such as exposed piping or protruding electrical 40 switches, and it is believed that a panelled appearance for interior walls is unlikely to prove generally acceptable.
- 45 It is an object of the present invention to devise a building construction which will permit the use of more durable, fire-resistive materials at a minimum of cost. The invention is characterized by the fact that a large percentage of the fabrication 50 and other work involved can be transferred to a factory, and thereby placed upon a quantity production basis.

55 It is a further object of the invention to devise a building construction which can make use of prefabricated panel units, which can be as-

sembled in such a manner as to allow a choice in selection of individual house designs, without entailing a great number of different sizes and varieties of individual panel units. Another object of the invention is to provide concealed 5 spaces for the accommodation of electrical conduit, water and gas piping, and the like, without deviating from the standard character of the fabricated panel units. In this connection the invention is characterized by the fact that the 10 panel units are fabricated to certain standard dimensions, and when erected, intervening vertical spaces are formed between the adjacent panels. The lateral distance as measured between the center lines of these spaces correspond 15 to a given dimensional increment or multiple thereof, and as will be presently explained, these spaces, together with any structural members, conduit, piping and the like which may be contained therein, are concealed upon completion 20 of the wall.

Further objects of the invention will appear from the following description in which the preferred embodiments of the invention are set forth in detail in conjunction with the accompanying 25 drawings. It is to be understood that the appended claims are to be accorded a range of equivalents consistent with the state of the prior art.

Referring to the drawings:

Figure 1 is a floor plan of a building constructed in accordance with my invention.

Fig. 2 is a view illustrating one form of panel which can be employed.

Fig. 3 is a cross section taken on the plane indicated by line 3—3 of Fig. 2.

Fig. 4 is a cross section taken along the line 4—4 of Fig. 2.

Figs. 4a, 5, 6, 7 and 8 illustrate the manner in which various junctions between the panels can 40 be constructed.

Fig. 9 is a vertical section through one of the walls of a two-story structure constructed in accordance with the invention.

Fig. 10 is an elevational view of part of a wall 45 of a two-story structure.

Fig. 11 is a cross section taken on line 11—11 of Fig. 10.

Fig. 12 is a cross section taken on line 12—12 of Fig. 11.

Figs. 13, 14 and 15 are detail views illustrating a manner in which structural steel sections can enter into the construction.

Fig. 16 is a vertical sectional view of a wall utilizing a modified form of panel.

Figs. 17 and 18 are further details of the construction.

Figs. 19 and 20 illustrate one manner in which piping and electric wire conduits can be accommodated in the structure.

Figs. 21 to 29 are cross sectional views thru the junction of abutting panels and illustrate modified forms of panels and the manner in which the various types of panels can be joined to one another.

Referring to the floor plan of Fig. 1, both the exterior walls 10 and the interior walls or partitions 11, are indicated as constructed in accordance with the present invention. The units from which these walls are constructed are panels 12, and between the vertical edges of adjacent panels are vertical spaces 13. The distance 14 indicated on Fig. 1 is the actual width of each single panel, and the distance 16 is the dimensional increment which is utilized as a basis for the building design to be presently explained. It is obvious that all of the panels 12 cannot be identical, as provision must be made in the construction of certain panels for doors, windows and the like. For example panels 12a have openings to accommodate doors, panels 12b have openings to accommodate windows, panel 12c has an opening to accommodate a fire place. Likewise certain of the walls may include double or triple panels. For example panel 12d, which has an arched doorway opening, is a double panel, and the distance between the centers of the vertical spaces adjacent to the edge portions of this double panel, is exactly twice the standard dimensional increment 16 previously mentioned. Such interior arches may also be formed by the omission of a panel as at 15. Panel 12e is a triple panel and is provided with an opening for a wide window. Likewise panel 12f is a double panel to accommodate a window of greater width or optional location than might be provided in a single panel.

The advantages of utilizing standard increments as the basis for the dimensioning of room sizes, as measured between wall centers will be apparent. It is obvious from the description of Fig. 1 that considerable flexibility and latitude is afforded in the design of a floor plan, it being merely necessary for the designer or architect to utilize the arrangement and number of panels that will give rooms of dimensions approximating those desired, and that will enable the approximate positioning and numbers of windows and doors, as desired. Obviously minor deviations from a given design, as for example the provision of closets and cabinets, can be built upon the main structure, by ordinary methods. Various plumbing, lighting and heating fixtures are indicated on this typical floor plan.

In Figs. 2 to 4 inclusive there is shown a representative form of panel unit which can be utilized in my invention. This panel unit is substantially rectangular in shape, and is formed by a metal frame consisting of side vertical structural members 21, and top and bottom structural members 22 and 23 respectively. Reinforcing bars 24 join together the members 21 and serve to strengthen the frame. Diagonal bracing members 25 brace the panel frame and the erected wall as a whole. The body 26 of the panel can be conveniently formed of suitable cementitious material, preferably having insulating properties, as for example a hollow cement slab or a slab composed of aerated concrete or of concrete utilizing an aggregate of cellular structure such as pumice. Such materials are known in the art and need not be de-

scribed in detail. The body may either be solid or may be cast or formed with a hollow interior for the sake of lightness, but such hollow interior will not be accessible for accommodating conduit or piping installed during erection.

It will be noted that the upper structural member 22 of the panel is shown as being of channel shape to afford a groove. Likewise the lower structural member 23 is also of channel shape but is arranged to form a tongue which will interlock or interfit with the groove formed by frame member 22 of a lower panel. Such tongue and groove panel edges can be cast of the body filling material without use of horizontal framing members 22 and 23, tho the latter comprise a desirable reinforcement for the panel. Structural members 21 in this instance are likewise channels, and it will be noted that the width of these members is substantially less than the thickness of the panel body 26. Thus as shown in Fig. 4 members 21 form parallel shoulders 27 which are set inwardly with respect to the side surfaces of the panel body 26. The usefulness of shoulders 27 will be presently explained. In order to enable convenient connection between one panel and other adjacent panels, or to other necessary structural members, each panel can be conveniently provided with projecting threaded studs 28 when erection involves bolted connections. Obviously welding may be used for making erection connections as well as for fabricating the panel frames.

In forming a junction between the adjacent edge portions of two panels, an arrangement such as shown in Fig. 5 can be employed. In this case the vertical edge portions of the two panels are spaced to form the intervening vertical space 29. This space can be utilized for accommodating piping 30, electrical conduit, and the like. Vertical cover strips or slabs 31 are arranged to cover and enclose space 29, and these slabs are shown seated upon shoulders 27. In order to secure slabs 31 in place, they can be provided with apertures 32 thru which tie wires 34 can be passed and fastened around rods 33 which are positioned in such apertures. Slabs 31 are of such thickness that their outer surfaces are substantially flush with the side surfaces of the panel body 26, and they are made of similar material, and suitably reinforced by metal rods, mesh or backing. Suitable cementitious material, plaster, or other filler 36 can be disposed between the edges of slabs 31 and adjacent portions of the panels, to provide smooth joints. Vertically spaced connecting members 35 are secured to members 21 by means of studs 28 and serve to connect members 21 to form the equivalent of a hollow post or column. Since panel framing members 21 function as such posts and transmit vertical stresses, they will be of metal and possess considerable structural strength. After the panels are erected and cover slabs installed, the exterior wall surfaces can be covered with a surface coating 37 of stucco or other suitable material. The interior surface of the wall can be covered by a thin layer 38 of plaster, paint, wall paper or other finish.

A suitable corner junction for walls formed of such panels is shown in Fig. 6. In this case the space 41 between the vertical edge portions of the two panels, is enclosed by an outer angle slab 42. Tie wires 43 serve to retain this slab in position in contact with the outer shoulders 27. Space 41 is concealed upon the inner side of the wall by plaster or cement 44. Members 21 in this instance are connected by vertically spaced members 45.

Fig. 7 illustrates a T junction between walls formed of such panel units. In this case the space 48 formed at the junction between the walls, is enclosed on the outer side of the walls by the 5 slab 49, which is likewise held in position by tie wires 51. At intersecting wall joints space 48 can be enclosed by cement or plaster 52. Vertically spaced tie members 50 in this case serve to connect members 21 of adjacent panels.

Fig. 8 illustrates a junction between main walls of a building and an interior partition. It may be explained at this point that certain non-bearing interior partitions of a building constructed in accordance with my invention, need not have the thickness or strength required for exterior or interior bearing walls. In this case the space 53 at the intersection between the walls is simply enclosed by the plaster or cement. The vertical structural members of the adjacent wall panels 10 are tied together by the metal straps 60 and the vertical member of the partition panel connected thereto by straps 56.

By referring to the vertical wall section of Fig. 9, it is possible to secure a comprehensive idea as to the manner in which panel units can be assembled to form a wall for a two story building, and how the floors, ceilings, and roof can be assembled together with the wall. In this case a lower row of panel units 61, corresponding to the exterior panel units 12 of Fig. 1, extend substantially one story in height, and assembled upon top of panels 61, there is a row of panels 62 enclosing the second story. The lower panels 61 illustrate a type containing hollow cores between wall surfaces, while the upper panels 62 are indicative of substantially solid slab filling material. The lower edge of panel 61 rests upon a suitable foundation wall 63. This foundation is provided with a channel sill member 64 adapted to interlock with the lower structural elements 23 of panels 61. Likewise the lower structural members 23 of the upper row of panels 62, have an interlocking engagement with the structural members 22 of the lower panels 61. The roof deck 66 can be interlocked with the upper structural members 22 of the upper row of panels 62. Aligned recesses 67 are shown on the inner faces of the lower row of panels 61, to accommodate a floor structure 68. Reinforcing shelf angle member 69 can be embedded in each of the lower panels 61, to form an adequate bearing for floor structure 68. Obviously the floor 68 can be made in any desired manner, either of wood or of fire-proof materials. It is possible to make it of panel construction of dimensions corresponding to those of wall panels as previously described. Near the upper edges of the lower panels 61 are the aligned recesses 70 for accommodating a ceiling slab 71. Continuous strut angles 72 extend the length of the wall and are connected at joints between panels thereby serving to align such panels in a straight wall, such angles occurring at top of wall and at intermediate floor levels. A somewhat different type of construction has been illustrated for the upper floor deck. In this case a wood subjoist 74 bears on the shelf angles 76 which are embedded in the bottom of recesses 73 in each panel. An upper floor wood deck 77 is supported by subjoists 74. The upper edge portions of panels 62 are likewise aligned by continuous strut angle 78 and are provided with recesses 79 for receiving the ceiling slab 81. This ceiling can likewise be made in panels of suitable dimensions corresponding to the dimensional increment spacing of wall panels.

Figs. 13, 14 and 15 indicate a suitable manner in which steel sill members, steel joists, and steel truss members, can be supported by a wall such as indicated generally in Fig. 9. In this case the lower ends of the structural members 21, of two adjacent panels forming the first story portion of the wall, are tied together by the U-shaped members 96. This member 96 can of course be electrically welded to structural members 21, or bolted thereto by means of the studs 10 28, and can engage an anchor bolt projecting upward from the foundation thru the sill channel. Joists 84 are shown in the form of I beams. The lower flange of each joist is connected to members 21, by means of members 97 and 95. Member 98 is a seat angle to support the end of I beam 84 and is secured to the foundation channel 64. The upper ends of the structural members 21 for the lower panels, are tied together and spliced to the lower ends of the structural members 21 of 20 the upper panels, by means of a member 99. The steel joists 88, which are also shown in the form of I beams, are secured at their ends to member 99 by means of angle members 101 and to the continuous angle strut 72 (see Fig. 15). The 25 upper portions of the structural members 21 of the upper panels, are secured together by the member 103. Members 99 and 103 can be secured to structural members 21 by welding, or by means of the threaded studs 28 shown in Figs. 2 and 4. 30 The horizontal structural members 92 of the roof truss are secured to the upper panel sections 103, by angle members 104, and the continuous angle strut 78.

By reference to the construction shown in Figs. 35 13 and 14, it is evident that the spaces between the panels for the lower story will sometimes be in alignment with and in communication with the spaces between the panels for the upper story. Therefore conduit, piping, and the like can be 40 extended thru these spaces from the basement to the upper story, or from the attic to the lower story. However this will not be true where double or triple width panels occur in the first or in the second story walls and not in both.

The method of locking together the upper and lower rows of panels for a two story building wall is somewhat different in Fig. 16, than as previously described with reference to Fig. 9. In this case the lower edge of the frame for each panel 50 is formed by a light pressed sheet metal member 107, which is bent channel shaped to provide a groove. Likewise the upper edge portion of each panel is formed by a frame member 108 which also can be made of light metal similar to the 55 lower member 107, and which is channel shaped to provide a projecting tongue. In assembling such panels they interlock with horizontal structural members in the form of channels 109. For example one channel 109 is placed upon the foundation as a sill and forms a tongue interlocking with the lower edges of the first row of panels. An intermediate channel 109 is interposed between the upper edge portions of the lower row of panels, and the lower edge portions of the 60 upper row of panels. Likewise an upper channel 109 extends along and is interlocked with the upper edge portions of the upper row of panels. Such channels 109 comprise continuous strut members extending the length of the wall.

In Fig. 16 a modification is illustrated for the body construction of the panels. This modification consists in providing a waterproof membrane 110, made of suitable material such as tar paper or sheet metal, which extends in a general direc- 75

tion parallel to the planes of the faces of the panel, and which is crimped or formed in such a manner that the divided portions of the cementitious body are interlocked together. A 5 waterproof membrane can also be provided by sheathing the interior sides of the panels with sheet metal, as will be presently explained.

In Figs. 17 and 18 there is shown another suitable method for connecting together the members 10 21 of the adjacent panels and also for connecting lateral joists 58 to the composite wall. Such joists comprise I beams provided with extension angles 111, projecting at each end. These angle members 111 bear on and are connected to angles 15 112, which are bolted, or welded, to the adjacent ends of structural members 21 of the panel units, and to the horizontal channel sill or strut 109 of Fig. 16. A similar arrangement can be utilized for roof truss connections to the composite wall, 20 and probably has superior strength to the type of connections and of angle struts illustrated in Figs. 13 to 15 inclusive. It has the disadvantage however of interrupting the vertical spaces between the panels for the lower and upper stories, though 25 this can be overcome as will be described later.

Figs. 10, 11 and 12 convey a better idea as to the manner of forming a wall for a two story building by assembling panel units such as have been previously described. In these views the 30 surfacing of stucco or other suitable material upon the surfaces of the wall, has been omitted for the sake of clarity, and certain details, as for example the manner of interlocking the panels, correspond with Fig. 16. Thus referring to Fig. 35 10, 12 indicates a single plain panel such as referred to in the description of Fig. 1. Panel 12a is likewise a single panel, but is provided with an opening for a doorway. Panel 12b is a single panel but is provided with an opening for a window. Panels 12f are double panels and are provided with central openings for windows. The joints or junctions between the panels indicated generally at 114, can be constructed substantially as shown in Fig. 5. Corner joints, indicated generally at 116, can be constructed substantially as shown in Fig. 6. It will be noted that in case of the double panels 12f, and also in the case of triple panels if they are employed, structural members are required for the upper edge, corresponding to the members 23 of Fig. 3. This 45 upper structural member in such double or triple panels must function as a beam to offset any weakening which may be occasioned by the window opening, and to support the structural members, such as roof truss, floor joist, or upper 50 story panel joint comprising a post, which will occur at intermediate spacing locations. Such beam member at top of multiple width panels may comprise a truss embedded in the body of 55 the panel.

Fig. 11 is substantially the same as enlarged cross section of Fig. 16. The lower floor 117 in this instance is shown as of wood construction and resting upon wood subjoists which are in turn 60 supported by main joists 58. Likewise an upper wood floor 87 of the same construction is shown supported by similar joists.

Figs. 19 and 20 illustrate diagrammatically an 70 arrangement of panels similar to those illustrated in Fig. 16, and serves to make clear the manner in which electrical conduits and various pipes can be extended thru the vertical spaces formed between the panels. Members 31 in this instance represent cover slabs as described with reference 75 to Fig. 5. The space confined by slabs 31, formed

between the adjacent vertical edges of the panels, is shown occupied by a vertical vent pipe 122, which extends thru the roof of the building. Pipe 123 represents heating, gas or water pipe provided with a horizontal connection 124 extending into the adjacent room. Another pipe 125 extends thru the floor of the second story, and pipes 126 and 127 are extended horizontally between the ceiling of the first and the floor of the second story. It will be noted that in passing from the first to the second story level, the piping must be offset to pass the channel 106. Piping and conduit can reach any vertical space between panels in any wall in the building by horizontal runs at floor or ceiling levels and upper and lower floor 15 risers need not be in alignment laterally in the wall.

In Fig. 20 electrical wiring conduit 128 is extended upwardly thru the space 29. A lighting fixture 131 communicates with this conduit, and 20 is mounted upon the inner cover slab 31. Likewise a switch 132 and convenience outlet 133 is installed flush with the cover slab 31 and is connected to conduit 129. Other conduits 134 and 136 can extend horizontally between the ceiling 25 of the first and the floor of the second story. In the event that members 109 are omitted, as in the arrangement described with reference to Figs. 13 to 15 inclusive, then it is obvious that conduit or piping need not be offset in passing one floor 30 to another.

It is obvious that the invention is susceptible to many modifications. The standard structural shape channel shown for vertical members 21 of the panel frames may be replaced by special sections, when erection connections are to be welded, of such shape that proper alignment of panels will be assured. Fig. 4a shows a channel shape 35 137 having a concave web portion, and the connecting members 35 comprise short lengths of pipe 40 which will fit against such curved web portions and be welded to each. Similarly top and bottom members 22 and 23 are subject to change and can be square edges if preferred.

In place of utilizing slabs 31 as shown in Fig. 45 5, the space between two adjacent panels can be covered by a plaster or mortar coating 141, shown in Fig. 21. To permit application of such a coating, the panels can be provided with protruding strips 142 of suitable metal reinforcement, such 50 as expanded metal lath. The edges of these strips can be embedded in the cementaceous material of the panel bodies at the time these panels are fabricated. Fig. 21 also indicates a hollow structure of the cementaceous material, corre- 55 sponding to that of panel 61 in Fig. 9.

Fig. 22 indicates a further modified form of panel junction in which the vertical edges of the panels consist of I-beam structural members 143. The body portions of such panels can be made 60 of cementitious material such as has been previously described, but in this instance the surfaces of the panels are sheathed with composition boards 146. Likewise the vertical spaces between the edges of the panels, are covered by composition board strip 147.

In Figs. 23 and 24 I have shown panel units 70 sheathed with metal. As for example in Fig. 23 the panel units designated generally at 151, consist of metal sheathing 152 secured to a suitable metal frame. One edge portion 153 of this frame is formed integral with the sheathing, while the other edge portion 154 is formed by a structural channel member. When the panels are assembled to form a wall, the spaces between adjacent 75

panels can be concealed by metal cover plates 156. The interior of the panels can contain a suitable filler, preferably a material which is heat insulating, and can conceal stiffening ribs to prevent bulging of the sheathing. The filler may be loose, as for example mineral wool or diatomaceous earth, or it may be a backing of felt or paper adhering to the sheathing, or in the form of a slab of aerated gypsum or like material encased within the panels. If exposed metallic surfaces are not desired, any suitable finish can be applied directly on the sheathing and cover plates, resulting in a smooth wall surface. The sheathing can be secured to the metal parts of the panel frame, by suitable means such as welding. Metal sheathing may occur only on interior surfaces, the exterior wall panels being filled with cementitious material to receive stucco exterior coating as previously described. Metal sheathed panels can also possess insulating properties if such panels are made air-tight, by continuous seam welding, and a partial vacuum created therein. It is evident however that this construction necessitates the use of sheathing having sufficient strength to withstand external atmospheric pressure, or which is provided with proper internal reinforcement or bracing.

The arrangement shown in Fig. 24 is similar to that of Fig. 23, although in this case both vertical edge portions of the panels are formed by channels 155. One of the cover plates 157 is offset outwardly from the adjacent surfaces of the panels, and is electrically welded to the adjacent edges of the panel sheathing. Such a construction affords a panelled appearance.

In forming panel units of metal sheathing, if the surface of the sheathing is to be exposed instead of being painted over or papered, suitable corrosion resisting materials can be employed. For example I can employ aluminum or an aluminum alloy, copper or copper alloys, or stainless steel.

The panel units which have been previously described have been characterized by the fact that the vertical edge portions of the units are in the form of structural members. As has been previously described, after these panels are erected, adjacent vertical structural members of the panel frames are connected together in such a manner that each pair of vertical edge members form the equivalent of a vertical post or column which supports a vertical loading. I have found that it is also possible to utilize separate posts of hollow construction which can accommodate conduit, piping and the like, and then to provide panel units having their edges so constructed that they can be interlocked with the posts or pilasters when assembled in the wall. Constructions of this character are shown in Figs. 25 to 28 inclusive.

Referring to Fig. 25, the panel units are designated generally as 166, and can be formed of molded or cast cementitious material, as for example of aerated concrete. Suitable metal reinforcement can be provided to add strength. The vertical edges of these panel units are provided with grooves 167, and also with beveled corners 168. The posts consist of channels 169 which are tied together in any suitable manner. Panel units 166 can be interlocked with channels 169 as shown, and the space 171 between channels 169, which can accommodate piping, conduit, or the like, can be concealed by the slabs 172, or can be covered with lath and plaster. In this case the exterior of the wall will likewise be

covered with stucco or equivalent material, while the interior surface can be covered with plaster or like material.

The construction of Fig. 26 is similar to that of Fig. 25, although in this instance a junction is shown between two walls. The adjacent panel of the wall extending at right angles to the other wall, is locked between strips 181 fabricated with channels 169.

In Fig. 27 the panel units 173 are provided with tongue shaped vertical edges 174 to interlock with a post formed by the outwardly faced angle members 175. The space 176 formed by the vertical post can be covered by a coating of plaster applied on metal lath 177 fastened to such posts.

In Fig. 28 the post 182 is shaped in the form of a pipe except that side longitudinal slots 183 are provided to permit access to the interior thereof. The adjacent edges of the panels 184 are provided with concave edged surfaces 186 adapted to interlock with post 182, and beveled cornices 187 facilitate fitting in of cover slabs 188, which conceal the post 182 and any conduit or piping within the same.

In the event that posts are employed separate from the panel units, it should be noted that these posts should not only be of such a character as to enable positioning of piping or conduit within the same, but that the distance between the line of centers of the posts or columns as measured laterally should preferably be a standard dimensional increment or multiple thereof.

In all of the modifications of my invention contained above, I have repeatedly made reference to the provision of vertical spaces for accommodating conduit, piping or the like. It is obvious that after the conduit or piping has been placed in the spaces, the remaining space may be entirely filled with a suitable material. Such construction has the disadvantage that the pipes or conduits are not readily accessible for repair, but has the advantage that the filler can provide insulation at such spaces. This filler may be of such material that it can support a part of the load, supplementing the structural post member. In the event that a filler of either variety is employed it is obvious that the surfaces of the filler can be finished so as to continue the continuity of the side walls of the panels and obviate the necessity of using the previously described cover slabs. Thus the resulting effect is substantially the same as with panel junctions previously described.

In connection with the modification described in the preceding paragraph, it is possible that the posts be merely sufficient to support erection of a building to one story height, after which the vertical spaces between adjacent edges of the panels can be filled in with concrete or equivalent material, to add strength and rigidity. Further construction can then proceed upon the structure which has been so strengthened. Thus in Fig. 29 there is shown such a skeleton post formed of spaced T members 191. These T members can be connected by hoop battons 192 welded thereto. The panel units 193 are provided with grooves 194 along their vertical edges, to form an interlocking engagement with T members 191. Suitable forms can be placed upon the sides of the panels, to enable pouring of a concrete filler 196. When this concrete has set the entire structure has been made relatively strong and rigid. Any piping or conduit to be lo-

cated with such filled spaces will of course be installed prior to pouring.

Where separate posts are employed, with panels located between same and interlocking therewith, the posts will be substantially one story in height as in other embodiments of my invention. However the panels for such construction need not necessarily be of corresponding height. For ease of erection and to utilize smaller, lighter units it can require several panels to fill one story height of wall though each such panel will extend the full distance between posts.

In conclusion, it should be noted that while the spacing of the joints between panels, which may also comprise hollow separate posts, is preferably a uniform dimensional increment, or multiple thereof, the increment selected may vary with different embodiments of my invention. Generally speaking, I prefer to select a spacing increment that will also be suitable for the spacing of floor joists, roof trusses and other structural members required in the complete structure. Thus all connections between such members and the walls will occur at the spaced posts and where panels are double or triple width same will occur at predetermined intermediate spacings at which points means for connections may be provided.

In connection with the described spacing system it has already been mentioned that floor decks and ceiling slabs may be fabricated in panel form in sizes corresponding to the standard increment, and this applies also to the roof deck. All supplementary structural members can be fabricated to fit such increment variations. Material such as flooring, interior trim, piping, conduit and the like can be cut to fit in the factory and in this way further savings in cost can be effected. Thus my invention reduces the labor required for erecting a building to the simple assembling of prefabricated units, eliminates the lathing operation as now required, reduces or eliminates the plastering operation, and permits many money saving economies.

I claim:

1. In a building construction, a vertical wall formed of a plurality of upper and a plurality of lower parallel panel units, said units being positioned in such a manner that spaces intervene between the vertical edges of adjacent panels, the spaces between the upper panels being aligned and in communication with the spaces between the lower panel units, whereby conduit and the like can extend vertically thru any two aligned spaces, and a hollow floor and ceiling structure associated with the lower edges of the upper panel units and upper edges of the lower panel units, the interior of said structure being in communication with said aligned spaces, the distance measured laterally between the centers of any two adjacent spaces being a standard dimensional increment or multiple thereof.

2. In a building construction, a plurality of vertical pre-fabricated panels arranged in groups aligned with two horizontal wall center lines intersecting at 90°, said panels being rectangular and placed in edge-to-edge relationship to form two vertical walls and each of said panels providing a section of a wall in a single unit, in plan the distances between the centers of joints between adjacent panels conforming to a standard dimensional increment or multiple thereof, the point of intersection of the wall lines likewise coinciding with the center of the corner joints, each of said panels in plan having such

an outline that its edges do not extend beyond two clearance lines drawn through each adjacent joint center which are at angle of 45° with respect to said wall center lines and at right angles to each other, whereby intermediate wall panels are interchangeable with corner panels adjacent said point of intersection.

3. In a building construction, a plurality of vertical, pre-fabricated panels of substantial thickness and of a height substantially equal to one story of the building, said panels being arranged in edge-to-edge relationship in alignment with two horizontal wall center lines intersecting at 90°, whereby two vertical walls are formed, in plan the distances between the centers of joints between adjacent panels conforming to a standard dimensional increment or multiple thereof, the point of intersection of the wall center lines coinciding with the center of the corner joint, each of said panels in plan having such an outline that its edges do not extend beyond two clearance lines drawn through each adjacent joint center which are at an angle of 45° with respect to said wall center lines and at right angles to each other, whereby intermediate wall panels are interchangeable with corner panels adjacent said point of intersection, there being vertically-extending spaces provided between the adjacent edges of the panels for accommodating conduit, piping, or the like.

4. In a building construction, a plurality of vertical, pre-fabricated panel units in edge-to-edge relationship and aligned with intersecting horizontal wall center lines to compose a plurality of vertical intersecting walls encompassing a floor area, said panels being rectangular and of a substantial thickness to form both side wall surfaces, in plan the distances between the vertical center lines of joints between adjacent panels conforming to a standard dimensional increment or multiple thereof and the points of intersection of the wall center lines coinciding with the centers of the corner joints, said panels being so outlined in plan that their vertical edges do not extend beyond clearance lines drawn through adjacent joint centers which are at right angles to each other and 45° with respect to said wall center lines, whereby intermediate panels of any wall are interchangeable with corner wall panels.

5. In a building construction, a plurality of vertical, pre-fabricated panel units in edge-to-edge relationship and aligned with intersecting horizontal wall center lines to compose a plurality of vertical intersecting walls encompassing a floor area, said panels being rectangular and of a substantial thickness to form both side wall surfaces, said panels also being of sufficient height to form one story of a building, in plan the distances between the centers of joints between adjacent panels conforming to a standard dimensional increment or multiple thereof and the points of intersection of the wall center lines coinciding with the vertical center lines of the corner joints, said panels in plan being so outlined that their edges do not extend beyond clearance lines drawn through each joint center which are at right angles to each other and 45° with respect to said wall center lines, whereby intermediate panels of any wall are interchangeable with corner wall panels, there being spaces between the adjacent edges of the panels extending substantially the entire height of the walls and serving to accommodate conduit, piping, and the like.

6. In a building construction, a plurality of

- vertical, pre-fabricated panels of substantial thickness and of a height substantially equal to one story of the building, said panels being arranged in edge-to-edge relationship in alignment with two horizontal wall center lines and intersecting at 90° whereby two vertical walls are formed, in plan the distances between the centers of joints between adjacent panels conforming to a standard dimensional increment or multiple thereof, the point of intersection of the wall center lines coinciding with the center of the corner joint, each of said panels in plan having such an outline that its edges do not extend beyond two clearance lines drawn through each adjacent joint center which are at an angle of 45° with respect to said wall center lines and at right angles to each other, whereby intermediate wall panels are interchangeable with corner panels adjacent to said point of intersection, there being vertically extending spaces provided between the adjacent edges of the panels, and a floor associated with the lower edges of said panels, space beneath said floor being in communication with the lower ends of said spaces, whereby conduit and the like can be extended from beneath said floor structure upwardly through said spaces. 5

8. In a building construction, a plurality of vertical, pre-fabricated panel units in edge-to-edge relationship and aligned with intersecting horizontal wall center lines to compose a plurality of vertical intersecting walls encompassing a floor area, said panels being rectangular and of a substantial thickness to form both side surfaces of said walls, said panels also being of a sufficient height to form one story of a building, in plan the distances between the centers of joints between adjacent panels conforming to a standard dimensional increment or multiple thereof and intersections of wall center lines coinciding with respective centers of corner joints, said panels in plan being so outlined that their edges do not extend beyond clearance lines drawn through each joint center at an angle of 45° with respect to said wall center lines and at right angles to each other whereby intermediate panels of any wall are interchangeable with corner wall panels, there being spaces between the adjacent edges of the panels extending substantially the entire height of the walls, and means for providing continuing wall surfaces over said spaces to complete said walls. 15
